UNITED STATES PATENT OFFICE.

ROBERT ESNAULT-PELTERIE, OF PARIS, FRANCE.

CONTINUOUS-ACTION SYNCHRONIZER.

Application filed July 12, 1921. Serial No. 484,266.

To all whom it may concern:

Be it known that I, ROBERT ESNAULT-PELTERIE, citizen of the Republic of France, residing at 43 Boulevard Lannes, Paris,

5 Seine, in the Republic of France, have invented certain new and useful Improvements in Continuous-Action Synchronizers, of which the following is a specification.

The present invention has for its object to 10 provide means for synchronizing the moving parts of direct-acting fluid pressure motors or pumps. The invention is particularly designed for that type of direct-action engine as described and illustrated in the 15 specifications of English Patents Nos. 118,091 and 124,418. In such engines the moving parts transmit their energy directly to the fluid to be acted upon, each part moving under the action of a force such as is 20 generated through the explosion of a combustible mixture, or by any other means.

It is necessary that in these engines the moving parts shall have a synchronous movement and particularly in the most simple case where there are only two parts having a constantly inverse synchronous movement.

The present synchronizer is described for the case of two moving parts of equal masses 30 moving constantly at inverse speeds, practically nearly equal. The person skilled in the art will at once conceive, by the application of the theorem of the quantities of movement, the modifications of detail necessary to the case in which the two moving parts would have different masses and strokes.

In the simple case taken as an example, as 40 well as in the others, the material realization of the apparatus can only be an approximate image of its theoretical conception and the action of the forces (friction and others) in particular could not be avoided which may not be equal in both 45 directions. It follows therefore that the centre of gravity of the whole of the movable parts belonging to the same pair departs slightly from its normal mean position which it ought theoretically to maintain.

50 The object of the present synchronizer is to restore constantly towards its mean position the said common centre of gravity which it departs therefrom and that during 55 the entire stroke or travel of the moving

parts, it does not employ any device for transmitting the useful power of the motor or pump, and this point is particularly important.

The description about to be given with 60 reference to the accompanying drawing, given by way of example, will render the manner in which the invention is carried out properly understood.

Figure 1 is a perspective view of a synchronizer constructed according to a first mode of carrying out the invention, and having racks and springs of a powerful kind.

Figure 2 is a detail of one of these parts. 70
Figure 3 is the detail of another part.

Figures 4 and 5 represent the disconnecting devices for starting.

Figure 6 represents a synchronizer constructed according to a second mode of carrying out the invention, and comprising hydraulic pumps and liquid springs. 75

Figure 7 is a constructional modification.

Figure 8 is a complete view of the synchronizer shown in Figure 6. 80

Figure 9 represents an auxiliary pump.

Figures 10, 11 and 12 show, in elevation, plan and transverse section respectively, a practical mode of constructing the disconnecting device. 85

Figure 13 is a similar view to Figure 12, showing the position occupied by the disconnecting blade after it has been pushed into its operative position.

In the simplest method of carrying out 90 the invention (that illustrated in Figure 1), each of the moving parts carries a rack, as for example *a* which drives the piston by the finger *a*¹, and *b* that which drives the cylinder by the finger *b*¹. In Figure 1 the outer 95 guides of the racks have been omitted for sake of clearness in the drawing.

These two racks parallel to the direction of movement are turned face to face and gear with one or more pinions *c*, *c*¹. This 100 pinion or these pinions are carried each by a shaft *d*¹ (see Figure 2) which is not rigidly connected to the fixed frame of the motor or pump and this point is particularly pointed out as being very important. The said 105 shafts *d*¹ are each carried by a member *d*, *d* (see Figures 1 and 2) which is adapted to slide parallel with the direction of the movement, but which is retarded in its movement by suitable springs *e*, *e* which tend always

to bring the members *d*, *d* back into their normal position and thus constitute the active part of the synchronizer.

The members *d*, which in this example are two in number carry fingers *f*, visible in Figure 2, which engage between the springs *e*, which are themselves placed in seats made in a fixed part of the motor and abut at their ends against the shoulders *g* which are constructed to leave a free passage for the fingers *f*. In this way, the springs *e* are caused to act in both directions on the fingers *f*, as is easy to understand by simple inspection of the drawings and constantly draw the two moving parts towards their symmetrical positions with respect to their normal point of crossing. In other words, they tend constantly to bring back the common centre of gravity of the two moving parts into its normal position when it departs therefrom.

It is necessary that the motor thus arranged may be able to be started, for example according to a device similar to that described in the specification of applicant's copending application for patent Serial No. 242,856, that is to say that it shall be possible to cause by external means several alternate successive movements of the moving parts in order to fill the explosion chambers with fresh gases, and then to produce a spark at the moment of compression in one of the chambers, while leaving the moving parts free at the same instant in order to permit them to obey the explosion. To this end the rack of one of the moving parts, *a* for example, has a notch *h* cut therein (see Figures 1 and 3), adapted to be engaged by a hook *i* formed on one end of a rod *j*. This rod is reciprocated by operating a crank *m* through the interposition of a connecting rod *j*¹. This method of operating will be understood by a simple inspection of Figure 1 and the slight flexibility of the springs *e* renders the same possible without the stroke of the two moving parts being too different.

In order to produce the filling strokes, it is necessary that the hook *i* and the connecting rod *j* be maintained in their operative position and for this purpose the connecting rod *j* has a groove *l* in the interior of which slides a finger *n* carried by a member *o* which itself can slide in a direction at right angles to that of the alternate movement of the connecting rod *j*.

This member *o* is constantly subjected to an upwardly lifting force such as that exerted by a spring *r* which tends, in the position shown in the drawing, to lift this member and also the connecting rod *j* thereby causing the hook *i* to disengage and emerge from the notch *h*. On the other hand however, this member *o* is maintained in its lower position by a hook *p* constantly thrust in the desired direction by a spring *p*¹ (see Figures 1, 4, 5 and 10, 11, 12) so that in this oper-

ative position that is in the position shown in Figure 1, the hook *i* is in engagement with and therefore drives the rack *a*.

In order that disconnection is produced at one end of the stroke and on the same side, the connecting rod *j* carries laterally an extension *q* in the interior of which is an adjustable screw *s* which, in its movement due to the crank *m*, comes quite near to the upper extension of the hook *p* without however touching it (Figure 4).

When it is desired to produce disconnection, a blade lever *t* is thrust in the direction of the arrow (see Figures 1 and 4) which thus becomes placed in front of the upper end of the hook *p* (Figure 5). This blade *t* can be advantageously operated by a crank *t*¹ against the oppositely directed action of a spring *t*² (see Figures 10 to 13). When the screw *s* again reaches the end of its travel to the right, it strikes this time against the blade *t*, which is of sufficient thickness to permit a thrusting back of the hook *p*, clear of the member *o* thereby permitting the rod to be moved by the spring *r* which lifts the same abruptly thus causing the hook *i* to rise and emerge from the notch *h* and disconnect the movable parts.

At the moment when the hook *i* is lifted clear of the notch *h*, the member *o* which is electrically connected to earth by the spring *r*, touches by its end *o*¹ the spring *w*² and thus earths one of the poles of the two primary batteries or accumulators *A*¹—*A*² which are mounted in shunt. This contact constitutes a safety contact which prevents all possibility of ignition during starting.

The lever or rod *j* continuing to rise under the action of the member *o* and of the spring *r*, then strikes with its upper surface a rod *u* which is normally thrust downwards by a spring *v* electrically connected to earth. The head *u*¹ of the rod *u* which rests on the insulated contact or blade *w*, separates itself therefrom and, as in the disconnecting position, the rack *a* is on the right, its boss *x* is situated at this moment under that of the interruptor *y*¹ which is thus opened. It follows from this that the sudden opening produced between *u*¹ and *w* breaks the primary circuit of the coil *B*¹ and produces the first ignition.

The rod *u* continuing its upward movement under the action of the arm *j* and of the spring *r*, comes into contact with the spring *w*¹ and thus closes the earth contact of the circuit breaker *y*², allowing the same to act on the coil *B*² as the circuit breaker *y*¹ does on the coil *B*¹, each time the boss *x* of the rack *a* raises them towards the ends of its stroke.

To produce reconnection, pressure is applied to the stud *z*, but then two cases may arise: either the hook *i* is too much to the

left, when it strikes against the upper surface of the rack a and connection is only possible by turning the crank m until the hook i drops into the notch h , or the hook i drops into the gap on the right of the right hand end of the rack a , the connecting rod being free to descend and the member o engages with the hook p .

It is necessary that in this position and without turning the crank m the hook i may be able to place itself in the notch h . For this purpose the said hook is mounted in a flexible manner on the back of the connecting rod j (see Figure 3) and when this latter returns towards the left by a rectilinear movement by sliding over the finger p of the member o now engaged, the hook i mounts the ramp a^2 of the rack a assuming the dotted position of Figure 3 by reason of the flexibility of its portion i^1 as well as of the spring i^2 , then the said spring i^2 vigorously brings back the hook i into the slot h as soon as they fall opposite each other and the mechanism is ready for another start.

The synchronizer may be carried out, as has been said by means of pistons and liquid springs. In such a case, each of the moving parts carries a pair of oppositely situated pistons a^3 a^4 b^3 b^4 (see Figure 6) the two on the same side opening into the same chamber full of liquid v^3 v^4 . When the pistons a^3 a^4 move in one direction, they also compel, by the forcing back of the liquid in one of the chambers, the pistons b^3 b^4 to move in the other direction and on the other hand if the volume of the two chambers v^3 v^4 is sufficient, the compressibility of the liquid plays the same part as the elasticity of the springs e e in the first case. There is therefore no need of any fresh explanation of the action of synchronization which is identical with that of the preceding mode of carrying out the invention.

In this hydraulic system however, it is necessary to see that the joints of the pistons (not shown in order to simplify Figures 6, 7 and 9) shall be absolutely tight and that it is even inevitable that those of one of the two chambers may be less tight than those of the other. The result is that in proportion to the working of the motor, one of the two chambers v^3 v^4 empties itself slightly and that the whole of the two movable masses is able to move slightly on this side. This is precisely what it is necessary to avoid.

For this purpose, a device is provided which forces back automatically the liquid to the side where it is lacking and does so whatever be the maximum stroke of the moving parts at the moment when this corrective action becomes necessary.

It is necessary therefore first of all to ar-

range a liquid pump which only utilizes, in order to act, the central part of the stroke of one of the movable parts in such a way that it acts itself if the total stroke is at this moment very small and which stores up the liquid under pressure either under an air bell or in a space sufficiently great to enable the elasticity of the liquid to replace that of the air in the bell. Such a pump will be described hereinafter.

In order to carry out the distribution of the liquid on the desired side, on each of the pistons b^3 b^4 for example, of one of the moving parts (preferably that which controls the pump just mentioned), a circular neck c^3 c^4 (see Figure 6) forming a valve is arranged in such a manner that it leaves a passage for the liquid during a very short time likewise distributed on either side from the instant in which the pistons a^3 a^4 pass at the middle of their stroke and at the moment likewise or at the end, of the forcing of the auxiliary pump.

Pipes d^3 d^4 then convey this liquid into cavities e^3 e^4 which are made in the fixed frame f of the synchronizer: the pistons a^3 a^4 each have laterally a longitudinal groove g^3 g^4 and a circular narrow groove n^3 n^4 which in the mean position of the piston a^3 falls exactly opposite the face of the orifice of the pipes i^3 i^4 each communicating with each of the chambers v^3 v^4 . If therefore the pair of pistons a^3 a^4 is exactly in the middle of its stroke at the same instant as the pair b^3 b^4 , as it should be normally, the liquid under pressure can flow through the cavities or chambers g^3 g^4 in the pistons a^3 a^4 the fixed chambers h^3 h^4 and then escape to the outside through the pipes h^3 h^4 . If on the contrary this part a^3 a^4 is situated for example too much to the right at the moment in which b^3 b^4 uncovers the chambers c^3 c^4 that is to say there is a loss of liquid in the chamber v^3 , the pipes e^3 , g^3 of the piston a^3 which in this case is more to the right than it is represented, the passage d^3 , the chamber e^3 of the piston b^3 and the tube j^3 cause the chamber v^3 to communicate with the liquid under pressure by the pipe i^3 while the chamber v^4 on the contrary communicates with the outside by the passage i^4 the pipes e^4 g^4 of the piston a^4 which is situated in this case more to the right than in the drawing, the chamber h^4 and the pipe h^4 . The result is that the chamber v^3 which is deficient in liquid admits a small quantity thereof while the other v^4 which contained it in excess, allows an equal amount to escape.

It is possible to carry out a similar system by seating the pistons inside each other, as is shown in Figure 7 (the letters on this figure correspond to those of Figure 6) and it is superfluous to repeat on this subject the explanations which have just been given.

To start this arrangement a box o^5 (see Figure 8) carries internally two racks shown dotted, one of which a can be controlled by the longitudinally movable rod j operated by the connecting rod j^1 and the crank m .

The other rack which is underneath the rack a and therefore cannot be seen in this figure is driven by a pinion, the end of the 10 fixed shaft of which can be seen at e^5 . The whole of the arrangement, rack and pinion, is quite similar to that which is quite visible in Figure 1 (except the fixity of the shaft of the pinion) but only serves here for starting and in no way for synchronization.

To this end, the box o^5 is pivoted to a shaft x^5 around which it can rotate in order to take up for example the position partially represented in dotted lines in Figure 20 8, and the shackle y^5 allows the rack a to follow the same movement. The box o^5 can thus accomplish a very rapid exhaust under the action of the spring r when it is quitted by the hook p .

25 This takes place when the end of the lever t is interposed in front of the adjustable screw s which is carried by the rack a and which at the end of its stroke, comes very near to the hook p without however touching it.

It is useless to repeat all the series of 30 electrical contacts which take place when disconnection is effected. The letters are the same as those of Figure 1 and thus allow of the finding of all the peculiarities of these electrical contacts in the description which has been given above.

For reconnection, it suffices to press upon the stud z ; the fingers a^1, b^1 may however 40 fail to engage the notches a^{11} , but the outer edges of these notches are externally slightly tapered as at a^{12} as shown in Figure 8, and by the double movement of the crank m , the fingers a^1, b^1 which are each carried by a 45 spring a^5, b^5 respectively, engage the said tapered portions and consequently engage their notches after movement of the crank m .

The pump intended to supply the oil for 50 compensating the losses is represented by way of example in the form of a particular construction (see Figure 9).

A group of pistons, for example the group $b^3 b^4$ carries towards its middle a member in the form of a lozenge a^6 which, when these 55 pistons $b^3 b^4$ return towards their central position, engages between two rollers $c^6 c^7$ and separates them. These rollers move the two bent levers $d^6 d^7$ pivoted at the fixed points $e^6 e^7$ and operating the rocker bar f^6 . 60 This latter pushes back the piston and compresses the spring h^6 thus driving the liquid through the force valve i^6 .

It should be noted that by this arrangement the forcing back of the liquid is completely terminated in both directions at the 65

precise moment in which the group of pistons $b^3 b^4$ passes through its central position.

When it passes beyond it the spring h^6 brings back the whole system into its original position and produces the drawing in of 70 a fresh quantity of liquid through the automatic valve j^6 .

In the case in which the moving parts would have to have different strokes, it is 75 obvious that the pinions in Figure 1 might be replaced in each case by a pair of pinions of different radii or by two half pinions of different radii. In like manner in this case the hydraulic pistons of Figures 6 and 7 would have to have unequal sections. 80

It is quite obvious that the different arrangements which have just been described by way of example are in no way limitative and that modifications may be made therein without departing from the scope of the invention. 85

The synchronizer which forms the subject matter of this invention, is particularly applicable, as well as its system of starting, to the direct transmission motors described 90 by the applicant in his application for patent under Serial No. 242,856, and Serial No. 277,115 but it is obvious that it is likewise applicable to all motors, machines or engines the working of which may depend upon a 95 similar mechanical problem.

Furthermore, the arrangement for starting described in the specification of Serial No. 242,856, and which has already been mentioned above, might likewise be applied 100 by means of certain slight constructive modifications, to the starting of motors, (or other machines) provided with the present synchronizer apart from its starter.

What I claim and desire to secure by Letters Patent of the United States is:—

1. A continuous action synchronizer comprising two members adapted to move in opposite directions and means interposed between said members for constantly drawing the mean centre of gravity of the two members towards and into a normal position. 110

2. A continuous action synchronizer comprising two members adapted to reciprocate in opposite directions, means for starting the reciprocation of said members means associated with said starting means for disconnecting said starting means at a desired moment and means interposed between said members for constantly drawing the mean centre of gravity of the two members towards and into a normal position. 115

3. The combination of two elements adapted to reciprocate in opposite directions and a device for synchronizing said reciprocating movement, said synchronizing device comprising members rigidly connected to said elements to reciprocate therewith and having means associated with said members 120

for preventing the mean centre of gravity of said members from deviating from a normal position.

4. In a machine of the type referred to a device for synchronizing two movable parts comprising members rigidly connected to and movable with said parts, means for starting the reciprocation of said members, means associated with said starting means for disconnecting said starting means at a desired moment and means interposed between said members for constantly drawing the mean centre of gravity of the two members towards and into a normal position.
- 15 5. In a motor of the type referred to a device for synchronizing two movable parts, comprising members rigidly connected to and movable with said parts, means for starting the reciprocation of said members, 20 means for disconnecting said starting means at a desired moment, means associated with said disconnecting means for preventing all possibility of ignition during starting and means interposed between said members for 25 constantly drawing the mean centre of gravity of the two members towards and into a normal position.
6. In a machine of the type referred to, a continuous action synchronizer comprising two members adapted to move in opposite directions and a member slidably mounted between said members, said slidably mounted member carrying an element frictionally engaging each of said members and fingers

which engage between springs mounted in seatings rigidly connected to a stationary part of said machine.

7. In a machine of the type referred to, a synchronizing device comprising two members each having a toothed surface facing the other and adapted to move in opposite directions, a member slidably mounted between said members, said slidably mounted member carrying one or more pinions which engage said toothed surfaces and having laterally protruding fingers which engage between helical springs mounted in seatings rigidly connected to a stationary part of said machine.

8. In a machine of the type referred to, a synchronizing device comprising two members each having a toothed surface facing the other and adapted to be reciprocated at the same speed but in opposite directions, a plurality of members slidably mounted between said first named members, said slidably mounted members each carrying one or more pinions which engage said toothed surfaces and having laterally protruding fingers which engage between helical springs mounted in seatings rigidly connected to a stationary part of the said machine.

In testimony whereof I affix my signature in presence of a witness.

ROBERT ESNAULT-PELTERIE.

Witness:

RAYMOND ECKERT.
